UNITED STATES PATENT OFFICE.

HERBERT L. SMITH, OF CLINTON, MASSACHUSETTS, ASSIGNOR TO CLINTON
WIRE CLOTH COMPANY, OF CLINTON, MASSACHUSETTS.

MACHINE FOR MAKING WIRE GOODS.

No. 830,018.

Specification of Letters Patent.

Patented Sept. 4, 1906.

Application filed May 19, 1905. Serial No. 261,110.

To all whom it may concern:

Be it known that I, HERBERT L. SMITH, of Clinton, in the county of Worcester and State of Massachusetts, have invented certain new and useful Improvements in Machines for Making Wire Goods, of which the following is a specification.

This invention relates to a new and improved machine for making wire fabric.

- 10 Figure 1 is a cross-sectional view of a machine constructed in accordance with my invention, the view being taken on line 1 1 of Fig. 2, showing, in effect, the end elevation of the operating mechanism of the machine, particularly that for effecting the welding and for effecting the placing of the stay-wire. Fig. 2 is a top plan view of so much of the mechanism as is necessary to illustrate the operation of the circuit-closers in connection 15 with the operation of the welding-jaws, this view being taken on line 2 2 of Fig. 1 looking in the direction of the arrows. Fig. 3 is a detail view showing, in front elevation, the two main shafts of the machine and the parts carried and driven by said shafts. Fig. 4 is a detail view showing the intermittent gears for driving the shaft that operates the plungers of the rear welding-jaws. Fig. 5 is a detail view of the intermittent gears operating the 20 plunger-rail that carries the front welding-jaws. Fig. 6 is a cross-sectional view on line 6 6 of Fig. 5 looking in the direction of the arrows, showing the arrangement of the shaft that drives the plunger of one of the rear 25 welding-jaws and also showing the gear and eccentric for driving the plunger-rail that carries the front welding-jaws. Fig. 7 is a detail cross-sectional view of the front plunger-rail, taken on a plane represented by line 30 1 1 of Fig. 2 and showing one of the front welding-jaws and its spindle, the same sectional view appearing in Fig. 1. Fig. 8 is a detail view of a part of the front of the plunger-rail, showing the method of mounting the 35 spindle of one of the front welding-jaws. Fig. 40 9 is a cross-sectional view on line 9 9 of Fig. 8. Fig. 10 is a cross-sectional view of the break-switch girth, taken on the plane represented by the line 1 1 of Fig. 2, the same sectional 45 view appearing in Fig. 1. Fig. 11 is a sectional view on line 11 11 of Fig. 10, showing the method of mounting one of the contact-points and its latch. Fig. 12 is a detail 50 diagrammatic view of the circuits. Fig. 13 is a

diagrammatic view showing the transformer 55 and its primary-circuit connection, showing the welding or secondary circuit and the connection of the welding-jaws with the welding or secondary circuit, and showing the magnet-circuit. Fig. 14 is a detail view, in side elevation and partly in section, showing one of the break-switches for the primary circuit open. Fig. 15 is a like view showing said primary-circuit-break switch closed. Fig. 16 is a detail perspective view, partly in section, showing one of the break-switch latches, its operating bell-crank, and framework or casting. Fig. 16^a is a like view with the framework or casting. Fig. 17 is a detail view showing, in perspective and detached, the casting or 70 framework for the latch and bell-crank shown assembled in Fig. 16. Fig. 18 is a perspective view showing the contact members carried by the front welding-jaws that close and open the circuit of the break-switch magnet detached and separated from one another. Fig. 19 is a detail perspective view of one of the rear welding-jaws and its plunger or spindle. Fig. 20 is a detail perspective view of one of the front welding-jaws and its plunger or 75 spindle. Fig. 21 is a detail perspective view showing one of the position-blocks supporting the front end of a front plunger-spindle. Fig. 22 is a detail perspective view of one of the break-switch frames. Fig. 23 is a detail 80 view of one of the break-switch contact-points and its bushing. Fig. 24 is a detail view, partly in section, showing one of the supports for movable contact-carrier frames of one of the break-switches. Fig. 25 is a detail view showing a rigidly-mounted movable contact-point of one of the break-switch frames.

1 represents the general framework of the machine, which, as shown, comprises suitable uprights and cross and longitudinal girths. The means for feeding the strand-wires 2 consists of a toothed wheel 34, carried on and driven by a shaft 35 in any desired way. Such toothed driving-wheel and its 95 operating mechanism is not new with applicant. (See patent to John C. Perry, No. 633,213.)

While I have shown in the drawings but one strand-wire 2, it is to be understood that 105 I may employ as many strand-wires as I desire, there being employed a toothed wheel 34 for each strand-wire, each toothed wheel op-

erating not only to draw its strand-wire 2 into the machine, but also to draw said strand-wire through the straightening-rolls 36.

The stay-wire 3 may be fed into the holders 5 by hand or in any desired way. Thereafter the jaw 6^a on the end of the lever 5 is operated by means of the levers 6 and 8 and their connections to remove the wire from the receiver 4 and carry it to the position shown in Fig. 1 against the strand-wire 2, where it is grasped by the welding-jaws. In place of this form of stay-wire-feeding mechanism any other form could be employed. The means shown for feeding the strand-wires 2 or the means shown for feeding the stay-wire 3 are not new with applicant and may be replaced by any preferred form of feeding means. My invention is addressed to another portion of the machine, and the feeding means are shown in elevation in Fig. 1 for the sake of completeness. The specific form of strand-wire feed shown is that disclosed and claimed in patent to John C. Perry, No. 633,213, and the specific form of stay-wire feed is disclosed and claimed in patent to said Perry, No. 313,823, dated February 27, 1906.

10, Figs. 2 and 3, represents a main shaft mounted in suitable bearings at the lower part of the machine. 11 represents a gear or pulley on one end of the main shaft 10, by which power is applied to said shaft from any suitable counter-shaft or motor.

Referring to Figs. 1, 2, 3, and 4, 12 represents an intermittent gear rigidly mounted upon the shaft 10. 13 represents a complementary intermittent gear rigidly mounted upon a shaft 14, that is arranged in suitable bearings in the rear of the machine above the shaft 10. The teeth and dwell-spaces in the periphery of the two gears 12 and 13 are so arranged that the gear 12 is driving the gear 13, and consequently the shaft 14, during each half-revolution of the gear 12, while during the other half-revolution of the gear 12 the latter is holding the gear 13 and the shaft 14 stationary.

20, Figs. 2, 3, and 5, represent two companion intermittent gears rigidly mounted upon the shaft 10 inside the framework. These gears each mesh with a complementary intermittent gear 21. 21, respectively. Each of the gears 21, Fig. 6, is rigidly mounted upon a sleeve 25, that in turn is loosely arranged on the shaft 14. The peripheries of the gears 20 and companion gears 21 are so arranged with teeth and dwells that the gears 20 hold the gears 21 against motion during half of the revolution of gears 20, then turn the gears 21 during one-sixth of a revolution of the gears 20, then hold the gears 21 against motion during one-sixth of a revolution of the gears 20, then drive the gears 21 during one-sixth of a revolution of gears 20, the work of the periphery of the gears 20 being

represented by one hundred and eighty degrees dwell, followed by sixty degrees drive; sixty degrees dwell, sixty degrees drive, in the order stated. The one hundred and eighty degrees dwell of the gears 20 is timed to act simultaneously with the one hundred and eighty degrees of gear-teeth or drive of the gear 12, while the one hundred and eighty degrees dwell of the gear 12 is timed to act with the one hundred and eighty degrees of the gears 20, that is made up of sixty degrees drive, sixty degrees dwell, followed by sixty degrees drive in the order stated.

26 26 represent two eccentrics, one beside each gear 21 and in like manner rigidly mounted upon a sleeve 25. Upon each eccentric 26 is arranged an eccentric-strap 27, each provided with an arm 28.

Referring to Figs. 1, 2, 5, and 7, 40 represents a girth arranged at the front of the machine and supported upon ways or guides 41 at each end of the machine and at the front side thereof. The free ends of the rods 28 are pivoted to ears 42 on the rear side of the girth 40. By this arrangement a predetermined series of movements and dwells are given to the girth 40, depending upon the arrangement of the teeth and dwells of the gears 20. Assuming the gears 20 to rotate in the direction of the arrow in Fig. 5 and the parts to be in the position shown, the sixty degrees of teeth or drive of the gears 20 will drive the gears 21 to effect a movement of the girth 40 to the front of the machine, as shown in dotted lines in Fig. 5. In this position the girth 40 will be held for the sixty degrees of dwell of the gears 20. During this sixty degrees dwell of the gear 20 the various mechanisms of the machine operate to feed the strand-wire, feed and cut the stay-wire, and place it against the strand-wire, as shown in Fig. 1. Thereafter the second sixty degrees of teeth of the gear 20 engage the gears 21, causing a movement of the girth 40 inward, the girth being held in its innermost position or full-line position in Fig. 5 during the one hundred and eighty degrees of dwell of the gears 20. It is during this latter position that the welding operation occurs. In the front girth 40 is arranged a series of plungers 43, Figs. 7, 8, 9, 13, and 20. The central part of each plunger 43 is cylindrical. The front end of each plunger 43 is reduced, as at 44.

46, Fig. 21, represents a block, there being one for each front plunger 43. These blocks 46 are arranged in suitable longitudinal grooves 47^a in the rail 40. (See Fig. 7.) Each block is formed with a reduced squared front lug 47, arranged in a slot 48 on the front of rail 40, that forms an extension of the grooves 47^a. By this construction the blocks 46, with their lugs 47, can be slid lengthwise of the machine to any desired point and then secured by means of a set-

70

125

130

screw 49 passing down through a part of the rail and entering a suitable aperture 50 in lug 47. Each block 46 and its lug 47 is formed with a hole 45, slightly larger than the reduced part 44 of each plunger 43, the extension 44 of each plunger 43 being arranged in said aperture 45 and adapted to slide therein.

51 represents a nut adapted to be secured upon the screw-threaded end 52 of the extension 44 in order to limit the inward movement of plunger and to secure predetermined adjustment of the spring 53, which is arranged about each plunger 43, one end bearing against its complementary block 46, the other end bearing against the rear end 54 of the head 56 of the plunger. When the nut 51 engages the front side of complementary block 47, the spring 53 will be under a predetermined compression. When the plunger 43 is forced back against the tension of the spring 53, due to the presence of the parts to be welded between the two welding-jaws, said spring 53 will then be under an additional compression sufficient to force its plunger 43 forward upon the softening of the material, after the manner set forth in the before-mentioned patent of John C. Perry, No. 813,823. As shown, the head 56 of each 30 plunger is squared and engages the upper and lower walls of a complementary longitudinal slot 57 in the rear wall of rail 40, the slot 57, the grooves 47^a, and the slot 48 forming continuations of chamber 58, that runs lengthwise of plunger-rail 40 between its ends. A pin 60 on top of each head 56 is arranged in a suitable vertical slot formed in the rear side of plunger-rail 40 and prevents a lateral movement of the head 56 and parts carried thereby. To each head 56 is rigidly secured a copper block 70, the latter being insulated from the head 56 by means of insulating material 71.

72 represents the front welding-jaw properly secured to the front of the copper block 70 in any desired way, the face of the front welding-jaw being grooved, as shown, in order to receive the cross and stay wires, Fig. 13. In a recess on the side of each head 56 is secured a casting 76, Fig. 18. Casting 76 carries a boss 77, formed with a longitudinal hole 78. The boss 77 is formed with a rear projecting flat strip 79.

80 represents a contact-spring secured on the end of that part of the casting 76 that carries the boss 77, spring 80 being arranged substantially over the hole 78.

90 represents a rod the front end of which has screw-threads, as at 92 and is arranged 60 in a fiber or insulating block 93.

94 represents a plate of conducting material carried by the insulating-block 93 and secured thereto in any desired way. This plate is formed with a projecting finger 95, which lies on the top of block 93. The plate

94 is also formed with a lug 96 on its under side carrying a set-screw 97 for connecting a wire 2^a in circuit with plate 94 and its finger 95. The rear end of each rod 90 is arranged in the recess 99 in an ear 100, formed on each lug 47. (See Figs. 8, 9, 21.)

98 represents a shoulder or collar rigidly secured on the rod 90, engaging a complementary shoulder in the recess 99 and serves to limit the inward movement of the rod 90. 75 The front end of the rod 90 is slotted, as at 101, for rotating the rod 90 to adjust the fiber block 93. 102 represents a nut loosely arranged about the end of the rod 90. This nut 102 is formed with screw-threads on its 80 periphery that engage complementary screw-threads on the inner wall of the hole 99. A spring 103 is arranged in the hole 99 about the rod 90, between the collar 98 and the adjustable nut 102. By this arrangement the 85 block 94 with its finger 95 is so positioned on the rod 90 with reference to the contact part 106 on the end of the under side of the spring 80 that the finger 95 will engage the contact part 106 to close the circuit through the magnets of the break-switches (see Figs. 13, 18, and 20) at that point in the forward throw of the front welding-jaw 72, due to the upsetting action of the spring 53, where it is desired to have the welding action stopped. The 90 movement given to the girth 40, as heretofore set out, is independent of the movement given to the plungers 43 by means of the spring 53. The movement given to the plungers 43 by means of the girth 40 is to 100 separate the front welding-jaws from the rear welding-jaws, to permit the feed of the material, the placing of new parts, and to also effect the closing action of the front jaws upon the parts to be welded. As each rear 105 welding-jaw is forced up to grip the work between it and its complementary front welding-jaw, this grip of the parts to be welded serves to put the springs 53 under additional compression, each spring 53 forcing its nut 51 outwardly a sufficient distance to effect the desired amount of upsetting motion to the plunger of the front welding-jaw.

Referring to Figs. 2, 10, 18, 14, 15, and 19, 110 120 represents a rear welding-jaw plunger, 115 there being of course a rear welding-jaw for each front welding-jaw and each connected to a separate plunger. Each plunger 120 is squared at its rear end 121 and on its front end carries a reduced squared part 122, adapted to reciprocate in complementary bearings in the central girth 123, Fig. 1. The rear end of each plunger 120 is provided with a roller 124, adapted to be engaged by a complementary cam 125 on the shaft 14. While in Fig. 2 120 only four plungers 120 are shown, it is to be understood that there will be any number of plungers desired in the machine, corresponding with the front plungers 43. In the form shown in Fig. 2 the cams 125 on the shaft 14 125 130

are staggered in such a way that a particular cam 125 will engage its complemental roller and leave it, or, in other words, will force forward its complemental plunger 120 and permit it to return before another cam 125 engages its complemental roller. It will thus be evident that while the front plungers 43 are all brought forward simultaneously and the strand and stay wires forced into recesses in the front welding-jaw 72 the complemental or rear welding-jaws are brought up singly in the form of machine here shown, although they might be brought up in groups or as otherwise desired. In the form shown in Fig. 2 the plunger 120 at the left has been advanced to effect the welding operation at that point. The other plungers 120 are at their rear position. Each of the plungers 120 is formed of two side bars spaced apart sufficiently to receive a spring 126. The rear end of this spring is arranged in a suitable recess in the rear end of the plunger, while the front end of this spring engages a plate 127, arranged between the two side bars of the plunger and held at its ends in the walls of the slot in the casting 123 in which the plunger-rails 120 move. By this arrangement as a plunger is forced forward by means of the cam 125 the spring 126 is compressed, and as the cam 125 leaves its complemental roller 124 the spring 126 moves the plunger 120 to its rear position.

Referring to Fig. 19, to the top end of extension 122 is secured a copper block 133, suitably insulated from said extension 122 by means of insulating material 134. To the front face of the copper block 133 is secured the rear welding-jaw 135, by means of a clamp 136, like the clamp 136 on the front welding-jaw, Fig. 20.

Referring to Fig. 10, 137 represents a lug secured at the top of each extension 122. This lug 137 is formed with ears 138. In these ears 138 is arranged a screw 139 with screw-threads between the ears 138. One end of the screw 139 is formed with a slotted head 140, while the other end of the screw projects through the ear 138 and may be secured from displacement by a cotter-pin or in any other well-known way.

141 represents a block formed with a screw-threaded aperture and in which is arranged the screw 139. By turning the screw 139 the block 140 can be adjusted to any desired position between the two ears 138.

142 represents a spring arranged on the screw 139 between block 140 and one of the ears 138 in order to take up lost motion.

143 represents a finger formed on the top of block 141 and having its operating-face toward the front of the machine.

160 represents a rail or girth extending lengthwise of the machine above and just in front of the girth 123. This girth 160 on its

lower face is formed with dovetailed flanges 65 161, upon which is arranged a series of clamps 162, maintained in the desired position of adjustment lengthwise of the machine and over a plunger 120 by means of a set-screw 163. From the under side of the front end of each bracket or clamp 162 projects a downwardly-extending arm 164, in which is formed an aperture 165 to receive a bushing 166 of insulating material. In this bushing is arranged a barrel 167, formed with a contact-point 75 168, the barrel 167 being adapted to move back and forth in the chamber of the bushing 166.

169 represents a reduced extension of the barrel 167 and extends out through the rear 80 end of bushing 166.

170 represents a spring arranged in the bushing 166 about the extension 169 between the inner end of the barrel 167 and the end of the bushing, this spring tending to 85 yieldingly resist movement of the contact-point 168. The end of the extension 169 is slotted, as at 171, in order to receive a wire α of the primary circuit.

172 represents a nut arranged upon the 90 threaded end of the extension 169 and adapted to pinch and hold the wire α in place in the slot 171 between the end of said slot and the walls of the slot. The lower end of the plate 164 is formed with two perforated ears 95 176. In each of the ears 176 is arranged the screw-threaded reduced end 177 of a pin 178. The ear 176 is pinched between a nut 179 and the shoulder of the pin 178, Fig. 24, thus maintaining the pin rigidly in position.

180 180, Figs. 17 and 25, represents two arms connected at their top by a perforated hub 181. Each of the arms 180 at their lower ends carry a hub 182 182, connected by a web 184, that in turn is formed with a perforated boss 185, midway between the arms 180. The arms 180, hub 181, web 184, and boss 185 constitute a movable carrier-frame for a rigidly-mounted contact-point. In the boss 181 is arranged a spool 186 of insulating material. 187 represents a contact-point formed with an enlargement or collar 188.

189 represents a reduced stem of the hub 188, arranged in the spool 186. The end of this stem is screw-threaded and formed with a slot 190, in which is arranged a wire α of the primary circuit. 191 represents a nut arranged upon the end of the extension 189 and pinching the wire α between the sides and end of the slot 190, nut 191, and a washer 192, arranged on the extension between the wire α and one end of the spool 186.

193 represents a washer between the opposite end of the spool 186 and the inner end of the hub 188. Each of the bosses 182 is arranged upon one of the pins 178 and free to slide thereon.

194 represents a coiled spring on each pin

178 between the inner side of boss 182 and the boss 176, the said spring tending to move the boss 182 away from the boss 176.

200, Fig. 16, represents a cylindrical latch 5 arranged in the hub 185, formed with an operating-face 201, arranged toward the rear of the machine and adapted for engagement with the operating-face of the latch 143, Fig. 10. The latch 200 is formed with an upwardly-projecting stem 202, arranged between the arms 180. The upper end of the extension 200 is slotted, as at 203.

204 represents a bell-crank lever pivoted at 205 between two parallel lugs 206 206, that 15 project downward from the bottom of the clamp or bracket 162 and at the rear end thereof. The horizontal arm 207 of each bell-crank 204 is arranged in the slot 203 of the stem 200 beneath the pin 208, the end of 20 the bell-crank having a slight play in the slot 203 between the pin 208 and the bottom of the slot.

209 represents a lug on the arm 207 back of the point where said arm engages the pin 208 in order to hold the hubs 182 on their respective pins 178 when the end of the arm 207 rises to lift the latch 200 out of engagement with the latch 143. The end of the vertical arm of each bell-crank 204 is provided with a keeper 210.

211 represents a magnet, there being one for each bell-crank 204. Each magnet is supported by two arms 214 214, that extend rearwardly from the clamp 162. Each magnet has one of its poles opposed to and in operative position to its complementary keeper 210, so that when the bell-crank 204 is in the position shown in Fig. 15 the latch 143 is in engagement with the latch 200. If now the 40 magnet be vitalized, it will attract its armature, lifting the horizontal arm 207 of the bell-crank and the latch 200 out of engagement with its latch 143, Fig. 14. As shown in Figs. 10, 11, the wires x are supported by 45 the ends of their respective contact-points, wires x forming a part of the contact-point.

220 represents an arm extending upward from the rear side of each clamp 162 and formed on its end with a hub 221, in which 50 are arranged two bushings 222 of insulating material. In these bushings 222 is arranged a wire bus-rod z , comprising the magnet-circuit.

z' represents a wire running from the wire 55 or bus-rod z to each magnet 211.

z^2 represents a wire of the magnet-circuit running from each magnet to a binding-screw 97 on the plate 94. (See Figs. 13 and 18.) The magnet-circuits and their complementary make-and-break mechanism are 60 shown diagrammatically in Fig. 12, from which it will appear that the wires z are given one or more turns around the core of the transformer and receive therefrom an induced current.

300 represents a transformer suitably mounted in the framework of the machine at the bottom and one side thereof, the transformer being suitably insulated from the machine. The secondary or welding coil of the 70 transformer terminates in two copper arms or bars 301 302, extending crosswise of the machine and at the bottom thereof, and the bar 301 stands directly beneath the front welding-jaws, while the bar 302 stands parallel with the bar 301, but beneath the rear welding-jaws. Each front welding-jaw is connected to the bus-bar 301 by a flexible copper bar 303. A like copper bar 304 connects the bus-bar 302 to each rear welding-jaw. By this arrangement the space between the welding-jaws is left entirely unobstructed by the transformers and free for passage of strand members 2 or a fabric. While in Fig. 13 but four sets of welding-jaws are shown, 80 any desired number may be employed within the capacity of the transformer. It will be further evident that, if necessary, I may have a transformer put on each side of the machine, depending somewhat upon the number of pairs of welding-jaws it is desired to use. Where two transformers are employed, their respective bus-bars would be independent from each other.

306 represents a generator or source of 90 power. A wire x runs from said generator and forms a part of the wire or bus-rod x , carried by the pins. The primary wire x leads from the generator to a bus-bar 307, that carries a series of contact-points 308. 95

309 represents a series of plungers each adapted to be operated by a cam 310, fast on the shaft 10, cams 310 being so arranged that they will operate the plungers 309 singly, corresponding to the manner in which the cams 105 125 operate the plungers 120. Each plunger 309 carries at its rear end a contact-point 311, insulated from the plunger and arranged opposite a complementary contact-point 308 of the bus-rod 307. A primary wire x leads 110 from the transformer to the bus-rod x . A primary wire x' runs from each contact-point 311 to the primary wire x leading from the transformer.

The operation of my improved machine is 115 as follows: The welding-jaws being in their retracted position, suitable mechanism, Fig. 1, feeds forward the strand-wires 2 and a new stay-wire 3 in proper position with relation to each other and to the welding-jaws. 120 Thereupon the rail 40 is drawn inward, carrying its plungers and the front welding-jaws to the position shown in Fig. 13, with the exception of the position occupied by the front plunger 56 in Fig. 13, the fingers 106 being 125 just at the rear of and out of contact with the complementary fingers 95. The cams 310 are placed on the shaft 10 in complementary relation to the corresponding cams 125 on the shaft 14 in order that the primary circuit for 130

a particular pair of welding-jaws may be closed, as the rear welding-jaw of that pair is forced forward, and the order in which this connection occurs may be arranged as desired. In the form as illustrated in Fig. 13 the front or left-hand cam 125 has thrown forward its plunger 120, while the complementary cam 310 has closed the primary circuit at that point, the primary circuit being closed now throughout the system through the pair of welding-jaws shown in the front of Fig. 13, since the forward motion of the plunger 120 forces the contact-points 187 168 into engagement with each other. As the metal of the members 2 and 3 softens, the springs 53 force forward the welding-jaw 70, thus contacting the fingers 106 and 95. This closes the magnetic circuit through the magnet 211 of that pair of welding-jaws, causing the disengagement of the latches 200 and 143 and the breaking of the primary circuit at this point and the cessation, consequently, of the welding action. The cams 125 and 310 are timed to permit the rearward movement of their respective plungers 120 and 309 at this point, thus bringing the welding-jaws out of contact with the parts 2 and 3.

Having thus explained the nature of my invention and described a way of making and using the same, although without attempting to set forth all of the forms in which it may be made or all of the modes of its use, what I claim, and desire to secure by Letters Patent, is—

35 1. In combination with the coöperative elements of a wire-fabric machine, means for feeding strand-wires, means for feeding a stay-wire, means for welding said wires at points of intersection, comprising a series of 40 pairs of welding-jaws, means for advancing half of said jaws, means for advancing the complementary jaws independently to grasp the work, a transformer, and an independent connection from each pair of welding-jaws to the secondary circuit of said transformer.

45 2. In combination with the coöperative elements of a wire-fabric machine, means for feeding strand-wires, means for feeding a stay-wire, means for welding said wires at 50 points of intersection, comprising a series of pairs of welding-jaws, means for advancing half of said jaws, means for advancing the complementary jaws independently to grasp the work, and means whereby one of each 55 pair of jaws has an independent and automatic upsetting movement.

60 3. In combination with the coöperative elements of a wire-fabric machine, means for feeding strand-wires, means for feeding a stay-wire, means for welding said wires at points of intersection, comprising a series of pairs of welding-jaws, a single transformer having a secondary coil whose two terminals are each extended to form a bus-bar, one-half of 65 said jaws being each independently connect-

ed to one bus-bar, the other half of said jaws being independently connected to the other of said bus-bars.

4. In combination with the coöperative elements of a wire-fabric machine, means for feeding strand-wires, means for feeding a stay-wire, means for welding said wires at points of intersection, comprising a single transformer, having each terminal of its secondary coil extended to form a bus-bar, a series of welding-jaws, a connection between each of said series and one of said bus-bars, a complementary series of opposed welding-jaws, and an independent connection between each jaw of said series and the other of said bus-bars.

5. In combination with the coöperative elements of a wire-fabric machine, means for feeding strand-wires, means for feeding a stay-wire, means for welding said wires at points of intersection, comprising a single transformer, each secondary terminal of which is extended to form a bus-bar, a series of welding-jaws, each of which is independently connected to one of said bus-bars, a complementary series of welding-jaws, each of which is independently connected to the other of said bus-bars, means for selectively closing the primary circuit through said single transformer for each pair of welding-jaws, and means controlled by each pair of welding-jaws for automatically breaking the circuit upon completion of the weld.

6. In combination with the coöperative elements of a wire-fabric machine, means for feeding strand-wires, means for feeding a stay-wire, means for welding said wires at points of intersection, comprising a series of movable welding-jaws, a series of complementary movable opposed welding-jaws, means for advancing the first series to grasp the work, means for selectively and independently advancing each jaw of the second series to grasp the work and close the primary circuit, and means operated by each jaw of the first series for automatically breaking the circuit upon completion of the weld.

7. In combination with the coöperative elements of a wire-fabric machine, means for feeding strand-wires, means for feeding a stay-wire, means for welding said wires at points of intersection, comprising a series of movable welding-jaws, a complementary opposed series of movable welding-jaws, means for advancing the first series to grasp the work, means for advancing each jaw of the second series independently and selectively to grasp the work, and means controlled by each pair of welding-jaws for breaking the primary circuit upon completion of the weld.

8. In combination with the coöperative elements of a wire-fabric machine, means for feeding strand-wires, means for feeding a stay-wire, means for welding said wires at points of intersection comprising a pair of

welding-jaws, each of which is movable, a break-switch, means controlled by one of said jaws for setting said switch before the welding operation, and means controlled by the other of said jaws to open the switch upon completion of the welding operation.

9. In combination with the coöperative elements of a wire-fabric machine, means for feeding strand-wires, means for feeding a stay-wire, means for welding said wires at points of intersection, comprising a transformer having each of its secondary terminals extended to form a bus-bar, a series of welding-jaws and an independent laminated connection between one of the bus-bars and each jaw of said series, a complemental opposed series of welding-jaws, and an independent laminated copper connection between each of said jaws and the other of said bus-bars.

10. In combination with the coöperative elements of a wire-fabric machine, means for feeding strand-wires, means for feeding a stay-wire, means for welding said wires at points of intersection comprising a series of pairs of welding units, means for advancing half of said welding units to grasp the work, means for selectively and independently advancing the complemental half of each welding unit to grasp the work, a source of power, means for connecting that source of power with each welding unit, and means controlled by each welding unit for automatically cutting out or disconnecting said unit from the source of power upon completion of the welding operation of that unit.

11. In combination with the coöperative elements of a wire-fabric machine, means for feeding strand-wires, means for feeding a stay-wire, a bonding unit composed of two opposed movable members, a source of power, means for connecting said unit to the source of power, an independent power-interrupter device, and means controlled by said unit for automatically actuating said device.

12. In combination with the coöperative elements of a wire-fabric machine, means for feeding strand-wires, means for feeding a stay-wire, a series of welding units each composed of two movable members, a source of power means for automatically and selectively connecting each unit with said source of power, an independent power-interrupter device for each unit, and means controlled by each unit for automatically actuating the interrupter device of that unit.

13. In combination with the coöperative elements of a wire-fabric machine, means for feeding strand-wires, means for feeding a stay-wire, means for welding said wires at points of intersection, comprising a series of welding units, each composed of two members, a source of power, means for selectively and independently connecting each welding unit with said source of power, an independent power-interrupter device for each welding unit, means controlled by one member of each unit for operating the interrupter device of that unit to operate the unit, and means controlled by the other member of each unit for automatically operating said device to disconnect the power from that unit at the completion of the welding operation.

14. In combination with the coöperative elements of a wire-fabric machine, means for feeding strand-wires, means for feeding a stay-wire, means for welding said wires at points of intersection, comprising a pair of welding members, each of which is movable, a source of power, a power-interrupter device, means controlled by one of said members for operating said power-interrupter device to connect the power, and means controlled by the other of said members for operating said power device to disconnect the power upon completion of the welding operation.

15. In combination with the coöperative elements of a wire-fabric machine, means for feeding strand-wires, means for feeding a stay-wire, means for welding said wires at points of intersection, comprising a series of welding members, a power device, an independent connection between said power device and each of said members, a complemental opposed series of bonding members, a power device and an independent connection between each of said members and said device, a source of power, means for connecting the latter with said power devices, an independent power-interrupter for each pair of welding units, and means controlled by said unit for automatically operating the power-interrupter and disconnecting the unit from the power device upon the completion of the welding operation of that unit.

In testimony whereof I have affixed my signature in presence of two witnesses.

HERBERT L. SMITH.
